(57) **CLAIM**

The ornamental design for the arithmetic and control unit for computer, as shown and described.

DESCRIPTION

FIG. 1 is a top perspective view of the arithmetic and control unit for computer showing our new design;

FIG. 2 is a front elevational view thereof;

FIG. 3 is a rear elevational view thereof;

FIG. 4 is a side elevational view of one side thereof;

FIG. 5 is a side elevational view of the other side thereof;

FIG. 6 is a top plan view thereof; and,

FIG. 7 is a bottom plan view thereof.

The broken lines showing of ports in FIGS. 1-3 are included for the purpose of illustrating unclaimed portions and form no part of the claimed design.
